UNITED STATES PATENT OFFICE.

HARRY L. VAUGHAN, OF CHICAGO, ILLINOIS.

THROAT FOR BOTTLING-MACHINES.

1,104,024.

Specification of Letters Patent. Patented July 21, 1914.

Application filed December 19, 1910. Serial No. 598,002.

To all whom it may concern:

Be it known that I, HARRY L. VAUGHAN, a citizen of the United States, residing at Chicago, in the county of Cook and State 5 of Illinois, have invented certain new and useful Improvements in Throats for Bottling-Machines, of which the following is a description.

My invention belongs to that class of devices known as throats for bottling machines for clamping crown caps on the necks of the bottles, and relates particularly to an improved throat and spring actuated dogs for retaining the crown in position, being in 10 the nature of an improvement over the device shown in my pending application, filed January 15, 1910, Serial No. 538,184.

My invention has among its objects the production of a throat and its parts that is 15 simple, durable, efficient and satisfactory, that may be used wherever found applicable.

To this end my invention consists in the novel construction, arrangement and combination of parts herein shown and described.

In the drawings, wherein like reference characters indicate like, or corresponding parts, Figure 1 is a sectional view of a throat embodying my improved construction. 20 Fig. 2 is a cross sectional view of the same, taken substantially on line 2—2 of Fig. 1. Fig. 3 is a cross sectional view taken substantially on line 3—3 of Fig. 1. Fig. 4 is an enlarged sectional view taken substantially on line 4—4 of Fig. 3. Fig. 5 is a perspective view of one of the resilient members. Fig. 6 is an enlarged sectional view, showing a modified construction.

Referring to the drawings, 1 represents a 25 tubular casing of suitable material provided with an inwardly extending flange 2 at one end, and extended as at 2¹ at the opposite end, this end being preferably threaded to afford engagement with a movable cap 3, which is provided with an 30 inwardly extending flange 4. The throat comprises two annular rings, preferably of a hard or enduring material, arranged within the casing 1 and provided with a shoulder 35 7 and tapering bore for forcing the edges of the cap or crown C inwardly to engage the bottle neck. The throat rings or pieces 5 and 6 are retained within the casing by the flanges 2 and 4. Any suitable means 40 may be employed for preventing movement

of the throat rings within the casing. As shown, I provide one or more pins or screws 8 in the casing, which engage with the ring 5. These pins, or their equivalents, may be arranged to engage the ring 6, if desired. 60 A more satisfactory construction, however, for preventing movement of the ring 6 is to provide lugs or extensions 9 on one ring, as shown on the ring 6, adapted to fit in depressions or recesses 10 in the other ring. 65 The throat pieces may be replaced when worn by removing the cap 3, and replacing one or both of the rings as desired.

To maintain the crown cap C in position when fed to the throat, before the same is 70 forced upon the bottle neck, I provide suitable dogs, or their equivalents, arranged to support the cap substantially as shown in Fig. 1. The dogs preferably comprise a plurality of balls 12 of hard or enduring 75 material. They are positioned in recesses 11 in the extended end 2¹ of the tubular casing, the ring 6 being provided with openings or holes opposite, or mating with the recesses 11. The openings in the ring 6 are 80 of slightly less diameter than the diameter of the balls or spherical dogs 12, so that the balls will extend into the bore, or into the interior of the ring, but not pass or escape through the holes. The balls are preferably 85 resiliently maintained in operative position, so that they will give to permit the insertion of the cap, and then spring out to support the same.

In the construction shown in Figs. 1 to 5, 90 I show two springs, each arranged to control a pair of dogs, it being understood that there may be any number of dogs desired. The springs comprise the ends 14 connected by shanks 14¹, and are positioned in the recesses 11, a portion of part of the extensions 2¹ being cut away as at 15 to receive the shanks 14¹. The springs are provided with holes 19 in the ends, through which the balls 12 partially extend, so that the balls 100 are maintained in position. They are also preferably offset or bent as at 16, so as to engage the notch 17 in the extended end 2¹, which prevents them from slipping endwise into the recesses, but permits them to be 105 readily removed after the cap 3 is unscrewed from the casing 1. The cap 3 may be locked on the tubular casing 1 by a set screw 18, or equivalent means, so that if 110 openings or holes 28 for the admission or

escape of fluids are provided in the cap and casing, the cap and casing may be locked with the holes alined.

As is obvious, the throat may be very readily dissembled by removing the cap 3 and removing the parts, and they may be readily reassembled, or new throat pieces or dogs inserted as desired. With the construction shown, one or both throat pieces may be replaced when worn, as may the balls 12. By using ball dogs they may be made very hard and wear uniformly, giving greater efficiency.

In the modified form illustrated in Fig. 6, the lining or throat pieces 21 and 21² are provided, same being formed so that there is a shoulder 21¹. The balls 12 are maintained in position by means of coiled springs 24, which bear against plates 22, which contact with the balls. The opposite end of each of the springs contacts with the removable plug 24 in the cap. In this construction the balls and springs may be removed at any time by removing the plugs 23, or by varying the position of the plugs, the pressure upon the balls may be varied as desired. The plate 22 in this construction maintains the ball in alinement with the hole in the throat piece, and affords a very satisfactory bearing for the spring 24.

Having thus described my invention, it is obvious that various immaterial modifications may be made in the same without departing from the spirit of my invention, hence I do not wish to be understood as limiting myself to the exact form, arrangement, construction or combination of parts herein shown and described, or uses mentioned.

What I claim as new and desire to secure by Letters Patent is:—

1. A throat attachment for bottling machines comprising a tubular casing, provided with an inwardly extending flange at one end thereof, a removable lining fitting within the casing comprising a plurality of annular abutting rings fitting within said casing and seated against said flange, the uppermost ring being provided with a tapered bore, and the lowermost ring being provided with a bore of greater diameter than the bore of said tapered ring and with an opening extending therethrough, a movable detent carried by the casing, and projecting through the opening in said lowermost ring, and means carried by the casing and underlying said lowermost ring to normally hold the lining within the casing.

2. A device of the kind described, comprising a tubular throat piece provided with a plurality of openings therethrough, a ball

of greater diameter than said openings positioned on the exterior of the throat at each opening and extending partially therethrough, and resilient means for maintaining said balls in operative position, comprising a spring for each pair of balls. 65

3. A device of the kind described, comprising a tubular throat piece provided with a plurality of openings therethrough, a ball of greater diameter than said openings positioned on the exterior of the throat at each opening and extending partially therethrough, and resilient means for maintaining said balls in operative position, comprising a plurality of springs having holes 70 provided therein and in engagement with said balls at said holes. 75

4. In a device of the kind described and in combination, a tubular casing having a flange at one end and a plurality of recesses at the opposite end, a removable tapering lining fitting in said casing and seated against said flange, said lining having an opening therethrough at each of said recesses, a ball of greater diameter than the 80 openings in said lining positioned in each recess and extending into the bore of the lining, and means for maintaining such balls in position, comprising a spring for each pair of balls, said springs provided with holes therein of less diameter than the 85 diameter of the balls, and arranged to contact with the balls with the same extending through said holes. 90

5. In a device of the kind described and in combination, a tubular casing having a flange at one end and a plurality of recesses at the opposite end, a removable tapering lining fitting in said casing and seated against said flange, comprising a pair of annular rings, one of said rings having an opening therethrough at each of said recesses, a ball of greater diameter than the 95 openings in said lining positioned in each recess and extending into the bore of the 100 lining, and means for maintaining such balls in position, comprising a spring for each pair of balls, said springs provided with holes therein of less diameter than the 105 diameter of the balls, and arranged to contact with the balls with the same extending through said holes. 110

In testimony whereof, I have hereunto signed my name in the presence of two subscribing witnesses.

HARRY L. VAUGHAN.
